UNITED STATES PATENT OFFICE

THOMAS W. B. WATLING, OF CHICAGO, ILLINOIS

DESIGN FOR AN AMUSEMENT APPARATUS

Application filed September 2, 1930. Serial No. 36,852. Term of patent 14 years.

To all whom it may concern:

Be it known that I, THOMAS W. B. WATLING, a citizen of the United States, residing in Chicago, county of Cook, and State of Illinois, have invented a new, original, and ornamental Design for Amusement Apparatus, of which the following is a specification, reference being had to the accompanying drawing, forming a part thereof.

The figure is a perspective of an amusement apparatus showing my new design.

I claim:

The ornamental design for an amusement apparatus substantially as shown.

THOMAS W. B. WATLING.
